A. C. SOULE,
WINDOW SASH MOUNTING.
APPLICATION FILED NOV. 30, 1914.

1,168,833.

Patented Jan. 18, 1916.

UNITED STATES PATENT OFFICE.

ARTHUR C. SOULE, OF SAN FRANCISCO, CALIFORNIA.

WINDOW-SASH MOUNTING.

1,168,833.

Specification of Letters Patent. Patented Jan. 18, 1916.

Application filed November 30, 1914. Serial No. 874,939.

To all whom it may concern:

Be it known that I, ARTHUR C. SOULE, a citizen of the United States, residing in the city and county of San Francisco, State of California, (whose post-office address is No. 226 Judah street,) have invented new and useful Improvements in Window-Sash Mountings, of which the following is a specification.

10 This invention relates more particularly to means for supporting sashes slidably pivoted in window frames.

Among the objects of this invention are to produce a mounting simple in construction, easily installed and adjusted; that will give to the sash, as nearly as may be, uniform support in its various adjustments, and evolutions; that is architecturally and commercially attractive; that will allow the sash 20 to be completely reversed and closed within the opening; that may be laid out, partially assembled and the interrelation of parts established in the factory, to facilitate its proper installation by the average workman 25 familiar with this class of labor.

Other objects and advantages will appear as the description progresses.

In the drawing accompanying and forming part of the present specification, to 30 which like reference characters have been applied, a simple form of putting this invention into practice is shown. I do not wish to be understood as confining this invention to the disclosures made in said drawing and description, as many variations may 35 be introduced, within the spirit of this invention, as defined in the claims succeeding the said description.

This invention involves the pivoting of 40 the sash, on opposite sides, on pivots frictionally engaging grooves in the opposite sides of the window frame, to permit the swinging of the sash in the window frame for ventilation. The movement of the sash 45 is controlled by a system of levers interposed between the sash and frame, to hold the sash in any fixed position desired, against wind pressure or other shifting forces. This type of sash is hard to control in its various evolutions by the ordinary means, owing to the 50 shifting balance of weight when the sash is shifted from the closed or vertical plane, to the full open or horizontal plane, and reversed and restored to the vertical plane, or 55 returned to the closed position without reversal. Heavy sashes are particularly hard

to control when opening or closing, in their departure from the vertical position. There is a period in the operation of a lever support in passing a center, at which the supporting power is comparatively nil, until the ratio of supporting power is again restored to the lever and removed from the sash, that is one of the lever elements in the combination of support levers.

In the present invention, the relative proportions and combinative actions of the various levers, are always in favor of the supporting mounting, as against the weight of the sash that is the load to be supported; 60 and permit the control pivot to be placed at or sufficiently near to the center of the sash to allow it to be completely reversed within its opening, and so close the opening in the reversed position, that weather is excluded, 65 a very substantial advantage in window washing during severe weather.

In the drawings Figure 1 is a perspective view of a conventional window frame, having upper and lower sashes mounted therein, 70 in accordance with this invention, the upper sash being shown in the open position and the lower sash in the closed position. Fig. 2 is a fragmentary enlarged detail of the sash and its supporting and control mounting, 75 with the window framing omitted. Fig. 3 is a fragmentary detail, practically full size, in cross section on the line III—III, Fig. 2, illustrating the interrelation of the sash, the guide weather strip, the control levers and 80 the side stile of a window frame. Fig. 4 is a similar view, illustrating the spring actuated sliding pivot mounted in the corner of the sash and bearing within the groove of the guide strip, all shown in cross section, 85 except the pivot and its actuating spring. Fig. 5 is an isometrical perspective from behind, illustrating the pivot plate for the carrier arm engaging the hinge plate of the 90 guide strip.

In detail the construction illustrated in the drawings, includes the window framing composed of the sill 1, the stool 2, the side stiles 3 connected across the top by the lintel 4, the usual stops 5 and other weatherproofing elements and finish. The side stiles 3 are provided with the grooves 6 on opposite sides of the frame, to receive the guide weather strips 7. These guide strips illustrated in cross section in Fig. 4 fit loosely 95 within the grooves 6, and extend from the sill 1 to the lintel 4, being cut to this proper

length in the factory, according to the measurement of the frame between the sill and the lintel. These guide strips are held within the grooves 6 by the hinge plates 8, provided with countersunk holes 9, to receive screws driven into the body of the strip 7, the plates 8 being gained into the strips flush with the surface. The angular extensions 10 of the plates rest against the surface 11 of the stiles 3, and are provided with countersunk holes 12 to receive screws driven into the stiles 3. These latter screws are not driven tight, and allow a free hinge movement of the strips 7 within grooves 6, permitted by the play of the screw in the opening 12, the purpose of which will be hereafter fully described.

The upper and lower sashes illustrated are alike in construction, arrangement and operation, except as to their location in the upper and lower portions of the window frame respectively. They include the side sash stiles 13 and 14 and the upper and lower rails 15 and 16 and 17 and 18 respectively. Owing to this similarity of the sashes, the following description of one sash will be understood to apply to both, as a window is often provided with one sash only, but may have any number of sashes in the same frame.

The opposite upper corners of the sash are provided with resilient pivots, (see Fig. 4) including the heads 19 engaging the grooves 20 in the strips 7, and the stems 21 having a shoulder 22 with the abutting washer 23, against which the end of the spring 24 bears. The whole is inclosed within a sleeve 25 crimped into the plate 26, gained into the side stiles 13 of the sash. The inner ends of the sleeves are turned in as at 27, to guide the end of the stem 21, and to provide an abutment for the opposite end of the spring 24 extending between the end of the sleeve and the washer 23. The combined tension 45 of the springs 24 forces the heads 19 against the bottoms of the grooves 20, with sufficient force to exert a friction equal to supporting the weight of the sash pivotally suspended on the stems 21. This amount of spring tension 50 is preferable but is not arbitrary. It may be more than sufficient to support the sash, as described, or it may be less, without materially affecting the operation of the control mounting; any excess tension would be overcome by the operator in manipulating the sash, and any deficiency of tension would be compensated for by the novel arrangement of the control levers.

The backs of the strips 7 are milled at an angle as at 28, and the holes 29 bored therein at the proper intervals, to receive the coil springs 30, expanding between the bottoms of the holes and the bottoms of the grooves 6. The combined tension of these springs 30 is considerably more than the combined tension

of the pivot springs 24, the purpose being to force the strips 7 tight against the sides of the sash, to make weatherproof the joint therebetween at 31 in the closed position of the sashes. The side stiles 3 are provided with the usual stops 5 overlapping the joint 31, and against which the sash lies in the closed position.

In the approximate center between the top and bottom rails 16-18 of the sash, the pivot plates 32 are gained into the sash stiles and fixed thereto by the screws 33, on opposite sides of the sash. To these plates the control arms 34 are pivoted at 35, the opposite ends of these arms being pivoted at 36 to the control links 37 pivoted at 38 to the plate 39, fixed to the side stiles 3 by the screws 40, adjacent to the guide strips 7. Intermediate the pivots 35 and 36, the support arm 41 is pivoted at 42 to the control arm 34, preferably slightly above the middle between the pivots 35 and 36. The opposite end of the support arm 41 is pivoted at 43 to the plate 44, having an offset portion 45 overlying the angle 10 of the hinge plate 8 and provided with a slot 46 engaging a hook 47, formed on the end of the plate 8, bent at an angle to the extension 10; these hooks act as indices to locate the plates 44. The plates 8 are fixed to the guide strips 7, in the proper exact position between their opposite ends, to properly locate the suspending pivots 43 of the support arms. This point is indicated by placing the sash or sashes in their proper relative position with the control levers in their proper position, the location of the plates 8 then noted on the strips 7, to which they are securely fixed and left thereon. The offset plates 44 are then unhooked from the plates 8, so that when the guide strips 7 are properly placed in the grooves 6 in the window frame, (wherever it may be located) it will bring the hooks 47 in the proper position to receive the plates 44, when the sashes are assembled within the frame, when the plates 44 may be securely fixed to the side stiles 3, by screws driven therein through the holes 48; insuring the proper interrelation and combination of the various elements contributing to the operation of the sash or sashes within the frame, without depending too much upon the discretion of workmen outside of the factory, where the embodiments of this invention are produced.

This invention operates substantially as follows, presuming the sash to be mounted in the frame as described, and resting in the closed position illustrated in the lower sash in Fig. 1, the control arm 34, the support arm 41 and the control link 37 lying parallel in vertical alignment adjacent to the outside of the sides of the sash; the pivots 38 and 43 being placed in vertical alignment and the upper end of the lever 34 offset as at 49, to accomplish this par-

allel nesting of parts; the length of the link 37 being proportionate to the location of the pivot 42, so that the link lies beneath the support arm 41 in the closed position.

5 The control lever mounting is duplicated on opposite sides of each sash, to insure the proper balance of the sash in its various evolutions.

To open the window, as illustrated in the 10 upper sash in Fig. 1, the operator pushes outward on the lower rail 18 of the upper sash, pushing it into the position shown. This carries the pivotal centers 35 outward, opening the control mechanism into the 15 relative position illustrated in Fig. 2. The outward movement of the control arm 34 swings the support arm 41 outward on its pivot 43; the outward swing of the lever 41 elevates the pivot 42, which causes the center 20 of the sash to move upward lifting the lower rail 18 and causing the descent of the upper rail 16, on the opposite side of the fulcrum represented by the pivots 35. The friction exerted by the pivot heads 19 in the 25 grooves 20, holds the sash in any position chosen by the operator, the overhanging weight of the sash being supported by the pivot 43, through the control arm 34 and the support arm 41. In the positions illustrated in Fig. 1 the weight of the sash is 30 below the pivotal centers 21; this tends to swing the pivots 35 inward and the pivots 36 outward, putting a tension on the link 37 and the support rod 41, offset by a compression force exerted between the pivots 35 and the pivots 21, the pivot 42 being the fulcrum of the lever 34. This condition 35 holds until the sash reaches the horizontal position, and those positions in which the overhanging weight of the sash is above the pivots 21, as in reversing the sash within the 40 opening of the frame, to present the normally outside surface of the glass to the inside of the room, for the purpose of washing, etc. With the overhanging weight of the sash above the pivot 21 (in the reverse position), the weight of the sash pulls outward on the pivots 35, putting a compression strain on the links 37 offset by the 45 tension always remaining on the support arm 41, in all positions of the sash. Since the weight of the sash is transmitted through the control arm 34 to the support arm 41, and is controlled in its movements largely 50 by the control arm 34, it is obvious that the more nearly the control arm approaches the vertical, with respect to the horizontal movement of the sash, the better will be the support and control exerted by this arm 34.

55 The logical way to meet this condition would be to extend the length of the arm 34 downward, to the point of conjunction with the vertical line of the window frame, at which point it would have to be slidably 60 pivoted, the mechanical objections to such a

construction are sufficiently evident. These objections are very simply obviated by controlling the nether end of the control arm by connecting it to the frame by the link 37. The tension and compression strains 70 intercepted by the link 37 are relatively equal in the various evolutions of the sash, the support and control of which is practically uniform in all of its various positions, owing to the peculiar distribution of the strains 75 across the various levers, all of the parts being positive in their actions, excepting the resilient, spring imparted friction, between the grooves 20 and the heads 19 of the sash pivot.

The upper sash is provided with the V shape groove 50 in the under side of the lower rail, to fit the tapered upper edge of the rail 15 of the lower sash. In closing the sashes the upper sash is closed first, then 80 the lower one is pulled shut, which forces the upper edge of the rail 15 into the groove 50 in the lower edge of the upper sash, making the joint between the sashes waterproof. When the lower sash is locked by 85 a suitable latch, neither of the sashes can be opened from either side until this latch is unlocked.

Having thus described this invention, what I claim and desire to secure by Let. 90 Patent is:

1. A window sash mounting including a frame; a sash slidably pivoted in said frame; support arms pivoted to said frame; control arms pivoted to opposite 100 sides of said sash and to said support arms intermediate the ends of the control arms; connecting links pivoted to the said control arms and to said frame.

2. A window sash mounting including a frame having grooves in the opposite sides thereof; strips in said frame having grooves in the frame; a sash having pivots slidably engaging said strips; control arms having one end pivoted to opposite sides of said sash; links pivoted 110 to said frame and said control arms; and support arms pivoted to said frame and to said control arms intermediate their ends.

3. A window sash mounting including a window sash; grooved guide strips on opposite sides of said sash; resilient pivots engaging said sash and slidably engaging the grooves in said strips; support arms engaging pivots fixed adjacent to said strips; control arms pivoted intermediate their ends to 115 said support arms, the upper ends of said control arms being pivoted to opposite sides of said sash; and connecting links pivoted to the lower ends of said control arms and engaging pivots fixed to the frame near said guide strips.

4. A window sash mounting including a frame having grooves in the opposite sides thereof; strips in said frame having grooves; plates fixed 120 on said strips and hingeably attached to said 125

- frame; a sash having pivots slidably engaging said strips; springs interposed between said strips and the bottoms of said grooves; control arms having one end pivoted to opposite sides of said sash; links pivoted to said frame and the other ends of said control arms; and support arms pivoted to said frame and to said control arms intermediate their ends.
- 10 5. A window sash mounting including a frame having grooves in the opposite sides thereof; strips in said grooves; plates fixed on said strips and hingeably attached to said frame, and having hooks thereon; a sash having pivots slidably engaging said strips; control arms pivoted to opposite sides of said sash, and pivotally connected to said frame; and support arms pivoted to said control arms intermediate their ends and to plates engaging said hooks on the hinge plates fixed to said strips.
6. A window sash mounting and control mechanism including a window frame; strips attached to opposite sides of said frame; a sash having pivots slidably engaging said strips; control arms having bent ends pivoted to opposite sides of said sash and links pivoted to said control arms and having pivot plates attached to said frame;
- 25 30 support arms pivoted to said control arms intermediate their ends; hinge plates attached to said strips and having hooks

thereon; plates pivoted to said support arms and attached to said frame engaging said hooks.

7. A window sash mounting including a frame having grooves in the opposite sides thereof; guide strips mounted in said grooves; a sash having pivots slidably engaging said strips; control arms pivoted to said sash and movably connected with said frame; support arms pivoted to said control arms and pivotally attached to said frame; and resilient members interposed between said guide strips and the frame.

8. A window sash mounting including a frame; guide strips mounted on opposite sides of said frame; springs interposed between said strips and said frame; a sash mounted between said strips; pivots mounted in said sash and slidably engaging said strips; pressure means interposed between said sash and said pivots and having less tension than said springs; and a control mounting interposed between said sash and said frame.

In testimony whereof, I have hereunto set my hand this twenty-first day of November, 1914.

ARTHUR C. SOULE.
